DESIGN FOR A FOWL KILLING DEVICE

Alfred Silfen, Berkeley, Ill.

Application March 11, 1944, Serial No. 112,875

Term of patent 14 years

(Cl. D11—1)

To all whom it may concern:

Be it known that I, Alfred Silfen, a citizen of the United States, residing at Berkeley, in the county of Cook and State of Illinois, have invented a new, original, and ornamental Design for a Fowl Killing Device, of which the following is a specification, reference being had to the accompanying drawing, forming a part thereof.

In the drawing:

Figure 1 is a perspective view of a fowl killing device showing my new design;

Figure 2 is a side view of the device; and
Figure 3 is an end view.

I claim:

The ornamental design for a fowl killing device, substantially as shown.

ALFRED SILFEN.
